[57] CLAIM

The ornamental design for an armchair, as shown and
described.

DESCRIPTION

FIG. 1 is a perspective view of an armchair showing my
design, taken from the front and to one side, looking down
obliquely; and,

FIG. 2 is a perspective view of the armchair of FIG. 1, taken
from the rear and to one side, looking down obliquely.
The side view of the armchair which has not been shown is
a mirror image of that shown in FIG. 2.
